United States Patent Office

Des. 219,837
Patented Feb. 2, 1971

219,837

RADIO RECEIVER OR SIMILAR ARTICLE

Ralph K. Schwitzgebel, 5 Pelham Road,
Waltham, Mass. 02154

Filed Jan. 23, 1969, Ser. No. 15,464

Term of patent 3½ years

Int. Cl. D14—03

U.S. Cl. D56—4

Fig. 1

Fig. 2

Fig. 3

Fig. 4

Fig. 5

Fig. 6

FIG. 1 is a plan view of a radio receiver or similar article showing my new design;

FIG. 2 is a front elevational view thereof;

FIG. 3 is a back elevational view thereof;

FIG. 4 is a right side elevation view thereof;

FIG. 5 is a left side elevational view thereof; and

FIG. 6 is perspective view thereof.

Portions of the drawing figures are shaded to indicate contrast in appearance.

I claim:

The ornamental design for a radio receiver or similar article, substantially as shown and described.
